UNITED STATES PATENT OFFICE

JOHN R. SEXTON, OF MERIDEN, CONNECTICUT

TINSEL CORD

Application filed November 4, 1929. Serial No. 404,536.

This invention relates to the manufacture of ornamental cord for tying packages and particularly to cord formed of a core that is spirally overlaid with lame or tinsel, that is, 5 thin metal ribbon or strands of contrasting color or of greater brilliancy.

The object of the invention is to, in a simple manner, produce a strong cord of this character which has a brilliant, variegated, scintillating appearance when put to use, and is especially attractive when wound into a ball.

This object is attained by running through a machine a cord of twisted or braided cotton, linen, or silk, of any bright color, desirably 15 red, and running parallel therewith one or more strands of lame or tinsel of contrasting color, as green, and at the same time winding in an open spiral about the core and lame or tinsel, one or more strands of contrasting 20 lame or tinsel of greater brilliance, preferably silver or gold, and thereby producing a cord that at different intervals sparkles with colors of different hue. Fig. 1 of the accompanying drawing shows on greatly enlarged scale a 25 short length of cord made according to this invention, the core of this cord being illustrated as twisted and wound with a single strand of lame or tinsel. Fig. 2 shows on the same scale a modification in which the core is 30 braided and is wound with a plurality of strands of lame or tinsel.

The core 1 of the cord may be twisted or braided cotton, linen or silk, preferably twisted cotton, dyed to any color, preferably 35 red. This core is run through a machine and at the same time there is run through the machine, so as to extend substantially parallel with the core, one or more small, thin strands or ribbons of bright metal or tinsel 2, commercially known as lame, which has a color 40 that vividly contrasts with the color of the core, as green. As the core and the parallel tinsel strands are passed together through the machine there is wound spirally and tightly 45 about them, preferably in a reverse direction to the twist of the core, one or more strands of tinsel 3 of a different color, which latter strands may desirably be of silver or gold color.

50 As the result of the laying of parallel

strands of tinsel of one color upon a twisted soft core of another color, and the spiral open winding over these strands of tinsel of a still different color, the finished cord under the natural distortion effected by the twist, 55 throws off from the background of the core, the brilliant metallic hues or sparkle of the parallel strands of tinsel and the brilliant contrasting hues of the wound strands of tinsel, at different localities, giving the cord strength 60 and imparting a variegated, scintillating appearance which is very attractive.

The invention claimed is:

1. A cord comprised of a core, a strand of tinsel of contrasting color extending parallel 65 with and on the surface of the core, and a strand of tinsel of a different color tightly wound spirally about the core and parallel strand.

2. A cord comprised of a twisted core of 70 soft material, strands of tinsel of contrasting color extending parallel with the core, and a strand of tinsel of a different color wound spirally about the core and parallel strands.

3. A cord comprised of a core of soft fibers 75 twisted in one direction, a bright metallic ribbon extending substantially parallel with and on the surface of the core, and a bright metallic ribbon wound spirally about the parallel ribbon and core in a direction opposite to the 80 direction of twist of the core.

JOHN R. SEXTON.
